UNITED STATES PATENT OFFICE.

WINFIELD S. GILMORE, OF NEW YORK, N. Y., ASSIGNOR TO CROUCH & FITZGERALD,
A CORPORATION OF NEW YORK.

GARMENT-RECEPTACLE.

1,028,206.

Specification of Letters Patent.

Patented June 4, 1912.

Application filed December 6, 1911. Serial No. 664,211.

To all whom it may concern:

Be it known that I, WINFIELD S. GILMORE, a citizen of the United States, and a resident of the borough of Manhattan, city, 5 county, and State of New York, have invented certain new and useful Improvements in Garment-Receptacles, of which the following is a specification.

This invention relates to garment receptacles, either permanently fixed or transportable.

It has special reference to convenient, reliable and economical means for supporting garments carried in such receptacle, so 15 arranged that when it is desired to close the cover of the receptacle said means may be readily folded or adjusted therein out of the way.

The invention consists of the features 20 hereinafter pointed out.

In the accompanying drawings, forming part of this specification, the invention is shown in the preferred form of its various embodiments, like reference numerals designating corresponding parts in the several views.

Figure 1 is a front elevation of the receptacle, its hinged cover being in open position and in vertical section. Fig. 2 is 30 a sectional elevation on the line II—II of Fig. 3. Fig. 3 is a sectional plan view on the line III—III of Fig. 2. Fig. 4 is a view similar to Fig. 2, partly broken away, and showing the extension piece for the hanger rack and associated parts in folded position ready for the cover to be closed. Fig. 5 shows a detail.

Referring now to the specific construction as shown in the drawings, 1 is the body 40 portion of the receptacle having the cover portion 2 hinged thereto along a vertical edge. Supported by convenient means within the body portion and projecting outwardly from the rear thereof is a hanger rack 3 adapted to support garment hangers 4. In the preferred arrangement the rack comprises a rod having its inner end provided with a supporting plate 5 fixed to the rear wall of the body portion, said rod being also supported along its length by a plurality of supporting hooks 6 secured to the top wall of the body portion and con-

necting with the lower side of the hanger rack 3 to leave the upper side of this rack unobstructed for the free sliding movement 55 of the hangers 4.

7 is an extension piece for the hanger rack 3 designed and arranged to be supported in alinement with the rack 3, when the cover portion is in open position.

8 is an arm projecting from the cover portion 2 and arranged to hold the extension piece 7 in alinement with the rack 3. This arm 8 is preferably pivotally supported at its inner end so as to swing in a vertical plane, dropping down and against the cover portion, as shown in Fig. 4, when the cover portion is about to be closed. It is also preferred to permanently hinge the inner end of the arm 8 to the cover portion 70 and to permanently hinge its outer end to the extension piece 7, as shown in the drawings. For this purpose the outer end of the arm may be provided with an eye piece 9, through which loosely passes the rod 7, 75 and at its inner end with an eye piece 10 through which loosely passes a pintle 11 carried by brackets 12 and 13 secured to the cover portion.

14 is a supporting leg extending upward 80 at an angle from the cover portion and into supporting connection with the extension piece 7. Means, secured to the cover portion, are provided for supporting this leg at its lower end, the arrangement being such 85 as to permit the leg to fold up against the cover portion. In the preferred form, a socket bracket 15 is secured to the cover portion in which the lower end of the leg is detachably supported. This enables the 90 upper end of the leg to be permanently connected with the extension piece 7 and the latter, when folded against the cover portion, to carry with it the leg 14, as shown in Fig. 4.

16 is a connecting piece for connecting the abutting ends of the extension piece and rack together when they are in alinement. This piece 16 is rotatably secured to the connecting piece 7 and makes a bayonet-joint connection with the end of the rack 3. The middle portion of the piece 16 is knurled so that it may be firmly grasped for turning, and is made of the same di-

ameter as the tubing of which the parts 3 and 7 are made to enable the hangers 4 to slide freely across the joint.

In operation, when the receptacle is closed 5 the hangers are supported on the rack 3 and the extension piece 7, arm 8 and leg 14 are in folded position against the cover portion, as shown in Fig. 4. When the 10 cover portion has moved into open position the extension piece 7 is then elevated to align with the rack 3, and the lower end of the leg is centered in the socket support 15, thereby bringing the parts into the position shown in Figs. 1, 2 and 3. The connecting piece 16 is then adjusted and the 15 hangers, with their suspended garments, may be slid outward from rack 3 onto extension piece 7, convenient for display or removal.

20 The invention is of special utility as a traveling case or trunk for salesmen.

Various changes may be made from the specific and preferred embodiment of the invention, as shown in the drawings, without departing from the scope of the invention.

What I claim and desire to secure by Letters Patent is:—

1. In a garment receptacle, the combination 30 of a body portion; a cover portion hinged to the body portion along a vertical edge; a hanger rack secured to the body portion and projecting outwardly from the rear thereof; an extension piece for the 35 hanger rack; an arm projecting from the cover portion and arranged to hold said extension piece in alinement with the hanger rack when the cover portion is in open position; a supporting leg extending upward 40 at an angle from the cover portion and into supporting connection with said extension piece; and means secured to the cover portion for supporting said leg at its lower end.

2. In a garment receptacle, the combination 45 of a body portion; a cover portion hinged to the body portion along a vertical edge; a hanger rack secured to the body portion and projecting outwardly from the rear thereof; an extension piece for the 50 hanger rack; an arm projecting from the cover portion and arranged to hold said extension piece in alinement with the hanger rack when the cover portion is in open position, said arm being pivotally supported 55 at its inner end so as to swing in a vertical plane; a supporting leg extending upward at an angle from the cover portion and into supporting connection with said extension piece; and means secured to the cover portion 60 for supporting said leg at its lower end.

3. In a garment receptacle, the combination 65 of a body portion; a cover portion hinged to the body portion along a vertical edge; a hanger rack secured to the body portion and projecting outwardly from the

rear thereof; an extension piece for the hanger rack; an arm projecting from the cover portion and arranged to hold said extension piece in alinement with the hanger rack when the cover portion is in open position; means for connecting the hanger rack and extension piece together at their abutting ends; a supporting leg extending upward at an angle from the cover portion and into supporting connection with said extension piece; and means secured to the cover portion for supporting said leg at its lower end.

4. In a garment receptacle, the combination 70 of a body portion; a cover portion hinged to the body portion along a vertical edge; a hanger rack secured to the body portion and projecting outwardly from the rear thereof; an extension piece for the hanger rack; an arm projecting from the 75 cover portion and arranged to hold said extension piece in alinement with the hanger rack when the cover portion is in open position, said arm being permanently hinged at its inner end to the cover portion so as to swing in a vertical plane, and permanently hinged at its outer end to said extension piece; a supporting leg extending upward at an angle from the cover portion and into supporting connection with said extension 80 piece; and means secured to the cover portion for supporting said leg at its lower end.

5. In a garment receptacle, the combination 85 of a body portion; a cover portion hinged to the body portion along a vertical edge; a hanger rack secured to the body portion and projecting outwardly from the rear thereof; an extension piece for the hanger rack; an arm projecting from the 90 cover portion and arranged to hold said extension piece in alinement with the hanger rack when the cover portion is in open position, said arm being permanently hinged at its inner end to the cover portion so as to swing in a vertical plane, and permanently hinged at its outer end to said extension piece; a supporting leg extending upward at an angle from the cover portion and into supporting connection with said extension 95 piece; and means secured to the cover portion for supporting said leg at its lower end.

6. In a garment receptacle, the combination 100 of a body portion; a cover portion hinged to the body portion along a vertical edge; a hanger rack secured to the body portion and projecting outwardly from the rear thereof; an extension piece for the hanger rack; an arm projecting from the 105 cover portion and arranged to hold said extension piece in alinement with the hanger rack when the cover portion is in open position, said arm being permanently hinged at its inner end to the cover portion so as to swing in a vertical plane, and permanently hinged at its outer end to said extension piece; a supporting leg extending upward at an angle from the cover portion and into supporting connection with said extension 110 piece; and means secured to the cover portion for detachably supporting said leg at its lower end.

7. In a garment receptacle, the combination 115 of a body portion; a cover portion hinged to the body portion along a vertical edge; a hanger rack secured to the body portion and projecting outwardly from the rear thereof; an extension piece for the hanger rack; an arm projecting from the 120 cover portion and arranged to hold said extension piece in alinement with the hanger rack when the cover portion is in open position, said arm being permanently hinged at its inner end to the cover portion so as to swing in a vertical plane, and permanently hinged at its outer end to said extension piece; means for connecting the hanger rack and extension piece together at their abutting ends; a supporting leg ex- 125

tending upward at an angle from the cover portion and having a permanent connection at its upper end with said extension piece; and means secured to the cover portion for 5 detachably supporting said leg at its lower end.

In testimony whereof, I have signed my

name to this specification, in the presence of two subscribing witnesses.
